UNITED STATES PATENT OFFICE.

ALEXANDER H. REINHOLD, OF DETROIT, MICHIGAN.

ENVELOP-OPENER OR PAPER-CUTTER.

No. 890,300.

Specification of Letters Patent.

Patented June 9, 1908.

Application filed October 7, 1907. Serial No. 396,162.

To all whom it may concern:

Be it known that I, ALEXANDER H. REINHOLD, a citizen of the United States, residing at Detroit, county of Wayne, State of Michigan, have invented a certain new and useful Improvement in Envelop-Openers or Paper-Cutters, and declare the following to be a full, clear, and exact description of the same, such as will enable others skilled in the art to 10 which it pertains to make and use the same, reference being had to the accompanying drawings, which form a part of this specification.

This invention relates to envelop openers 15 or paper cutters, adapted to be used to clip off a thin clipping of the end from an envelop.

In the drawings:—Figure 1, is a perspective of the machine. Fig. 2, is a front elevation of the rear part of the frame. Fig. 3, is 20 an elevation of the knife and the backing of the knife. Fig. 4, is a section on the line $x-x$ of Fig. 2.

A box-like case 1 contains a vertically reciprocating knife 2, and forms a chamber to 25 hold the clippings detached from envelops in the course of the use to which the article is intended. The knife 2, is secured to a reciprocating plate 4 that engages between the ends 5 and 6 of the case. At the rear of the 30 reciprocating plate 4 is a hanging frame-bar 7, which hangs from the top plate 8, and which is provided with seats 9, 10 and 11 for the reception of movable members 12, which bear against the back of the plate 4, and hold 35 the knife 2, into close engagement with the front wall 13 of the case. The pressure members 12, are each pressed forward by a spring 14 inserted in the cavity behind the pressure member. The pressure member 40 carries on its front or protruding end an anti-friction ball 15, resting in a seat in the pressure member, and the actual contact is between the anti-friction ball 15 and the back of the plate 4. To the plate 4 is secured a 45 stem 16, which rises through a suitable opening in the top plate 8, into a tubular housing 17, and into a cap 18, which telescopes over the tubular housing 17. The stem 16 is se-

cured to the cap 18 and to the plate 4, and within the housing 17; surrounding the 50 stem 16, is a spring 19, which engages between the bottom of the housing 17 and the inner face of the cap 18, and lifts the cap, the stem connected to it, the plate 4, and the knife attached to the plate. Through the 55 front wall 13 is a suitable aperture 20 for the insertion of the end of the envelop to be treated. The knife is so located with reference to the back plate 4, that, when in its upper position there is a clear opening underneath the cutting edge 21 of the knife, and the cutting face which bounds the lower edge of the opening 20. The lower edge 21 of the knife is inclined with respect to the cutting edge 22 of the case, and the depression of the 65 knife causes the two to engage with a shearing cut.

Preferably the instrument is made of a size and weight to be utilized as a paper weight on the desk.

70

The rear closure 23 of the case is preferably arranged to be attached to, or removed from the remainder of the case by springing the upper edge out from under the cover plate 8, and lifting the projecting pin 24 out from a 75 socket 26 in the bottom plate 25.

What I claim is:—

In a combined envelop clipping machine and paper weight, the combination of a hollow weight, a reciprocating knife contained 80 therein, means fixed to the knife whereby its possible travel within the casing is limited, means within said weight for yieldingly holding the knife in shearing position with respect to a complementary fixed shearing portion of said casing, and means for yieldingly holding said knife at the upper limit of its possible travel within said casing, substantially as described.

In testimony whereof, I, sign this specification in the presence of two witnesses.

90

ALEXANDER H. REINHOLD.
